UNITED STATES PATENT OFFICE.

GEORGE BURROUGHS, OF MONESSEN, PENNSYLVANIA.

CASE.

Application filed December 3, 1921. Serial No. 519,677.

To all whom it may concern:

Be it known that I, GEORGE BURROUGHS, a citizen of the United States, residing at Monessen, in the county of Westmoreland, 5 and State of Pennsylvania, have invented new and useful Improvements in Cases, of which the following is a specification.

This invention has for its primary object the provision of a combined cigarette and 10 match case adapted for personal use, and designed so that a cigarette and match are simultaneously ejected from the case through the instrumentality of a single operating element.

Another object of the invention resides 15 in the provision of a device of the above mentioned character which is very simple in construction, and one which can be manufactured and sold at a very nominal cost.

The nature and advantages of the invention will be better understood when the following detailed description is read in connection with the accompanying drawings, 20 the invention residing in the construction, combination and arrangement of parts as claimed.

In the drawings forming part of this application, like numerals of reference indicate similar parts in the several views, and 25 wherein:

Figure 1 is a view in elevation of the device constructed in accordance with the present invention.

Figure 2 is an end elevation.

Figure 3 is a vertical sectional view, showing 30 the cigarette compartment.

Figure 4 is a similar view, showing the match compartment.

Figure 5 is a transverse sectional view 35 taken through the device.

Referring to the drawings in detail, 10 indicates the casing referred to, which may be constructed from any suitable material and which may also vary in size and configuration 40 without departing from the spirit of the invention. The casing 10 is divided by a partition 11 into a cigarette receiving compartment 12 and a match receiving compartment 13, while beneath said partition 45 is arranged a partition 14 upon which the matches and cigarettes repose. One end wall of the casing 10 is provided with spaced openings of relatively different size, the opening 15 being of a size to receive a 50 match, while the opening 16 is of a size to receive a cigarette.

Arranged beneath the partition 14 is a rod 17 which is supported by the opposed end walls of the casing 10. Slidably mounted upon this rod is a cylindrical member 19 60 which is normally held adjacent one end of the rod through the instrumentality of a coiled spring 20 which surrounds the rod and bears against the cylindrical member 19. Rising from the cylindrical member 19 65 are lugs 21 and 22 which are slightly spaced, the space between the lugs receiving the lower edge of the partition 11. The lug 21 being utilized to force a match through the opening 15, and the lug 22 being utilized 70 for forcing a cigarette through the opening 16, incident to movement of the cylindrical member 19 longitudinally of the rod against the tension of the spring 20. Manifestly, a cigarette and match are simultaneously 75 ejected from the casing when use of such articles are desired. The casing is provided with a door 23 which permits access being had to the compartment 12, and the door 24 which permits of access being had to the 80 compartment 13. While any suitable means may be employed for actuating the cylindrical member 19, use is preferably made of a manipulating element 26 which has an offset extremity 27 connected to the cylindrical member 19, the manipulating element 85 operating through an opening in one end of the casing and being provided with a knob or the like indicated at 27. The invention is very simple in construction, and 90 can be manufactured and sold at a very nominal cost.

While it is believed that from the foregoing description, the nature and advantages of the invention will be readily apparent, I desire to have it understood that I do not limit myself to what is herein shown and described, and that such changes may be resorted to when desired, as fall within the scope of what is claimed.

What I claim is:

1. A receptacle, a partition dividing the receptacle into a match receiving compartment and a cigarette receiving compartment, one wall of said receptacle having 105 spaced openings, said openings communicating with said compartments, a rod arranged within the receptacle, a spring pressed member slidably mounted on said rod and designed to singly engage a match 110 and a cigarette, and means for moving said member from one direction to eject a match

and cigarette simultaneously through said openings.

2. A receptacle, a partition dividing the receptacle into a match receiving compartment, and a cigarette receiving compartment, doors controlling communication to the respective compartments, one wall of said receptacle having openings communicating with said compartments, a member 10 arranged to slide beneath said partition, said members being designed to singly en-

gage a cigarette and a match, means for supporting said member for sliding movement, yieldable means for normally holding said member at one side of the receptacle, and means for moving said member in a direction to eject a match and a cigarette through said openings. 15

In testimony whereof I affix my signature.

GEORGE BURROUGHS.
